UNITED STATES PATENT OFFICE.

ROBERT T. VARNUM, OF NEW YORK, N. Y.

DESIGN FOR AN INFLATED CUSHION.

SPECIFICATION forming part of Design No. 22,121, dated January 10, 1893.

Application filed September 14, 1892. Serial No. 445,907. Term of patent 7 years.

To all whom it may concern:

Be it known that I, ROBERT T. VARNUM, a citizen of the United States, residing at New York city, in the county and State of New

5 York, have invented and produced a new and original Design for Inflated Cushions, of which the following is a specification, reference being had to the accompanying drawings, forming a part thereof, in which—

10 Figure 1 represents a plan view of a cushion embodying the features of my design; and Fig. 2 is a perspective view thereof.

The design consists in a cushion having the inner margin of a contour simulating that of an egg, and an outer margin of a corresponding contour. 15

I claim,—

The design for an inflated cushion, substantially as herein shown and described.

ROBERT T. VARNUM.
